UNITED STATES PATENT OFFICE

CHARLES F. WALP, OF BERWICK, PENNSYLVANIA, ASSIGNOR TO AMERICAN CAR AND FOUNDRY COMPANY, OF NEW YORK, N. Y., A CORPORATION OF NEW JERSEY

SKID

Application filed September 28, 1929. Serial No. 395,863.

This invention relates to skids or platforms adapted to rest upon a floor or other flat surface for receiving articles to be moved from one place to another.

5 One object of the present invention is to provide a skid of the character described which is strong and durable and beneath which a lift truck may be inserted and then elevated to clear the skid from its support.

10 Another object of the invention is to provide a skid formed of a single metal pressing reinforced by channels secured to the under surface thereof.

15 A further object of the invention is the provision of a skid of the character described formed of a unitary pressing comprising sides and a top supporting surface; the whole reinforced by stiffening elements secured to the sides and supporting surface on the inner surfaces thereof.

20 A still further object of the invention is the provision of a skid which is devoid of bolts, rivets or other mechanical securing means whereby a substantially smooth top surface 25 and sides are provided, or, to be more exact, a surface which is devoid of projections such as bolt or rivet heads or the like.

Other objects and advantages of this invention will be apparent from the following 30 description taken in conjunction with the accompanying drawings, in which:

Figure 1 is a top plan view of the skid of the present invention, having a portion of the top surface broken away to disclose the 35 reinforcing elements;

Fig. 2 is a sectional view on the line 2—2, Fig. 1; and

Fig. 3 is a sectional view on the line 3—3, Fig. 1.

40 Referring now more particularly to the drawings in which similar characters of reference designate similar parts in the several views, in the form of the invention illustrated in the drawings, the skid comprises in 45 the main a body portion A, formed of a single metal pressing, having a top supporting surface 2 and downwardly flanged or bent sides 4 which latter define supporting legs for the skid.

50 The skid also comprises a plurality of

spaced reinforcing elements B in the form of flanged channels which are preferably spot welded or otherwise secured to the under surface of the skid as hereinafter to be described.

55 The channels are substantially U-shaped in elevation and comprise a main portion 6 secured to the under surface of the supporting surface 2 and the ends thereof are bent at an acute angle as at 8 and then directly 60 downward to form the vertical legs 10, the flanges of which latter lie against and are secured to the inner surface of the sides 4 of the body portion A of the skid. In practice the channels 6 are spot welded to the 65 skid body but obviously they may be otherwise welded thereto, as for example by means of an electric arc.

70 By providing the angle portions 10 in the reinforcing elements B it will be apparent that extremely sharp bends of the channels are avoided, thus simplifying manufacture of the skid and eliminating the possibility of straining the metal of the reinforcing elements and also providing a construction in 75 which the edge portions 12 of the skid are reinforced at 2 points, namely, the points 14 and 16. The main portions 6 of the channels B reinforce the top surface 2 of the skid body as will be apparent, while the legs 10 of the 80 channels B stiffen the sides 4 in an obvious manner.

85 The drawings herein disclose one embodiment of the invention but it is to be understood that they are for illustrative purposes only and that various changes in the form and proportions of the device may be made within the scope of the claims without departing from the spirit of the invention.

90 What is claimed is:

1. A skid formed of a single piece of metal provided with downturned flanges upon opposite sides defining supporting portions, and a plurality of separately formed flanged channels secured to the inner surface of the metal 95 and extending along and secured to the flanges.

2. A skid formed of a sheet of metal provided with downturned sides defining supporting portions, and a plurality of separate- 100

ly formed reinforcing elements comprising channels secured to the inner surface of the metal and having the ends thereof outwardly and then downwardly bent.

- 5 3. A skid comprising a sheet of metal defining a supporting surface, said sheet of metal having its side edges downwardly flanged to provide supporting legs, channel units secured to the under surface of the supporting surface and having the ends thereof outwardly bent to be spaced from the supporting surface and supporting legs and then downwardly bent and arranged against the supporting legs and welded thereto.
- 10 15 4. A skid comprising a sheet of metal defining a supporting surface and provided with downturned sides defining supporting legs, and separately formed U-shaped channel units welded to the under surface of the supporting surface and to the legs.
- 19 25 5. A skid comprising a sheet of metal defining a supporting surface, said sheet of metal having its sides downturned to provide supporting legs, and a plurality of spaced channel units welded to the under surface of the supporting surface and having their end portions outwardly bent to be spaced from the sheet of metal and then downwardly bent to lie against the supporting legs, said downwardly bent portions being welded to said legs.
- 29 35 6. A skid formed of a single piece of metal provided with a flat unbroken top surface and downturned flanges upon opposite sides defining supporting portions; and a plurality of separately formed flanged channels secured to the inner surface of the metal and extending along and secured to the downturned flanges.
- 40 45 7. A skid formed of a single piece of metal provided with a flat unbroken top surface and downturned flanges upon opposite sides defining supporting portions, and means for stiffening the metal sheet comprising a plurality of separately formed U-shaped units secured to the inner surface of the metal and extending along and secured to the supporting legs.

In witness whereof I have hereunto set my hand.

CHARLES F. WALP.
